INVENTOR

John H. Goodfellow

UNITED STATES PATENT OFFICE.

JOHN H. GOODFELLOW, OF LOWELL, MASSACHUSETTS, ASSIGNOR OF ONE-HALF TO JOSEPH W. PIPER, OF SAME PLACE.

COOKING OR HEATING STOVE.

SPECIFICATION forming part of Letters Patent No. 621,812, dated March 28, 1899.

Application filed June 23, 1898. Serial No. 684,317. (No model.)

To all whom it may concern:

Be it known that I, JOHN H. GOODFELLOW, a citizen of the United States, residing at Lowell, Middlesex county, and State of Massachusetts, have invented certain new and useful Improvements in Cooking or Heating Stoves, fully set forth in the following description and represented in the accompanying drawings.

- 10 This invention relates to improvements in heating and cooking stoves, &c., and such other apparatus in which there is a combustion-chamber and smoke-flues constructed therein for the passage of combustion, heat, and gases and in which passages there may be an accumulation of ashes and soot in the flues of such apparatus. Heretofore it has been customary to provide such apparatus with flue stop or door to be removed in various walls of the apparatus through which a scraper could be manipulated to rake out the accumulated mass of foreign matter, while others removed a portion of the oven-plate to facilitate the same purpose. The task being 15 obnoxious and laborious at times and often causing much dust to rise in the room or to reach the floor, a task being hard for a lady to perform, requires much skill in manipulating, for the agitations of the dust in the 20 flue with a scraper causes much to be carried back by the draft into the flues of the stove, while in the application of my improvements none of these objectionable features can occur, or the loss of a suitable scraper, 25 generally supplied with an apparatus, hinder or delay the cleaning of the flues to the annoyance of the operator when desired to have the stove in its best possible condition for baking; and my invention has for its object 30 to provide means always ready, quick, and easy to operate to remove the accumulated soot and ashes from said flues of such apparatus without any of the said objectionable features.
- 35 To this end my invention consists, in combination with a cooking or heating apparatus provided with gas and heat conducting flues, of a flue-strip supported free from the bottom of said passage and a tray or pan constructed 40 and arranged and adapted to pass beneath the flue-strip, whereby upon its removal from the flue the accumulated soot and ashes may be removed thereupon; and it further consists of the combination, with a cooking or heating apparatus provided with gas and 45 heat conducting flues, of a flue strip or strips supported free from the bottom of said passage and a tray or pan constructed and arranged and adapted to pass beneath the flue-strip and furnished with a matching flue-strip arranged to register therewith, whereby the products of combustion are directed and the accumulated soot and ashes may be removed thereupon; and it further consists of such other details of construction and operation as are hereinafter described, and pointed out in the claims.

the flue-strip, whereby upon its removal from the flue the accumulated soot and ashes may be removed thereupon; and it further consists of the combination, with a cooking or heating apparatus provided with gas and 55 heat conducting flues, of a flue strip or strips supported free from the bottom of said passage and a tray or pan constructed and arranged and adapted to pass beneath the flue-strip and furnished with a matching flue-strip arranged to register therewith, whereby the products of combustion are directed and the accumulated soot and ashes may be removed thereupon; and it further consists of such other details of construction and operation as are hereinafter described, and pointed out in the claims.

In the drawings, Figure 1 is a perspective view of a cooking-range, illustrating the application of my invention; Fig. 2, a rear end 70 elevation of a range with the end jamb A removed, illustrating distinctive features of my invention; Fig. 3, a vertical transverse section of Fig. 2 with rear end jamb in position; Fig. 4, a vertical section, and Fig. 5 a longitudinal section, illustrating a modification; and Fig. 6, a perspective view of my improved soot-tray removed from the stove.

Like letters of reference refer to corresponding figures in the drawings. 80

A represents the end jamb of a stove, C the end oven-plate, D the bottom oven-plate, L the bottom of the stove, and B the back of the stove, a portion of which forms the back of the oven and rear ascending flue Q, between 85 all of which plates the flues N Q and O P are formed, the two latter forming the horizontal flues between the plates D and L or beneath the oven R.

In Figs. 1, 2, and 3 my improvements are 90 shown as combined with a sheet-flue stove, while Figs. 4 and 5 illustrate them in what is commonly known as "diving" and "ascending" flue stoves. In the former the flue-strip b is omitted and the strip a arranged diagonally beneath the bottom oven-plate, which, as shown, may be connected thereto by suitable bolts a³ passing through members a², the lower edge of said strip being supported free from the bottom L. Longitudinally this strip 95 100

may be inclined, so that its highest edge adjacent to the door may be farther off from the bottom of the stove.

t represents inwardly-projecting flanges 5 formed on the side walls of the flue-passages, the object of which will hereinafter appear.

S is an elongated opening, which may be constructed in any of the side walls of the stove, communicating with the said flues, and

10 *I* is a door adapted to close the same, and *i* a drawer-pull or other suitable operating device.

As shown, *J* represents a pan or tray which may be made of any suitable material, such 15 as sheet or cast metal, and provided with shallow sides and end flanges, the upper edges of which may occupy a position beneath the flanges *t*, thus directing dust and ashes to the pan. One of the sides of said pan may be

20 rigidly connected to the door *I*, or it may be provided with an independent end or edge and placed within the flue-space free of the said door. As shown in Figs. 1, 2, 3, and 5, the said tray is provided with an auxiliary

25 flue-strip *d*, its top face *d* of suitable width and preferably inclined to correspond to the angle of the lower edge of the strip *a* and its width compensating for any inaccuracy in locating it in the pan, or it may be struck up

30 from the metal forming the tray. Thus when in line together with each other the products of combustion are directed from the flue *o* to *P* and *Q* by passing around the outer ends of their junction. In Figs. 4 and 5 the said strips

35 *a* and *d* are arranged to fit the requirements of a diving-flue stove, in which the upper face of the auxiliary strip *d* may be provided with a rabbet *w* and the lower edge of the flue-strip *a* extending into the rabbet. Thus when

40 moved into position longitudinally to form a junction with the strip they form sealing as well as matching edges and readily free themselves from each other as the pan *J* is drawn out through the opening *S* by reason of their

45 wedge-like action. In lieu of the auxiliary strip *d* the said strip *a* may be constructed to form a closed junction with the bottom of the pan, and its end may pass in and out of the notch *n* as the pan is withdrawn or replaced

50 and a raised surface or rabbet formed to be co-operated therewith made in the tray-bottom. A suitable bail *k* may be connected to the pan, by which it may be carried after withdrawal.

In some instances, if desired, separate pans 55 may be used, one on either side of the flue-strip *a*, which may form its junction with the bottom *L*, and the side of the strip provided with dust-directing flanges *t*, under which the edges of the pan may pass, the same as on its 60 outer edges, the said pans being connected to the door *I* or independent thereof, without departing from the spirit of my invention.

In operating this device, assuming that all parts are in position and the stove has been 65 used sufficiently to require cleaning, it is but necessary to sweep all dirt from the top of the

oven-plate into the flue *N* or *N* and *Q*, pound lightly the side plates of the stove and oven plates with hammer or poker to jar the dust from them into the flue *O* and *P*, when the 70 pan or tray may be drawn out with its contents by the drawer-pull, the bail *k* lifted from the bottom, and the tray carried to the ash-barrel, after which the same may be quickly placed in position. 75

When the flue *Q* extends up behind the rear oven-plate, as seen in Figs. 1, 2, and 5, the lower end, forming connection with the flue *P*, may be provided with a suitable soot-displacer *V*, the movement of which will cause 80 the soot resting therein to be directed into the pan, as shown in Fig. 3, consists of a triangular frame resting on the bed of the flue, and a connecting-rod *r* protrudes from the side and furnished with a suitable knob *v* to 85 reciprocate this rod in and out of the flue. The agitation of the scraper will quickly force the soot into the pan.

Having shown and described this invention as applied to cooking apparatus, it will be 90 readily understood that the same is equally applicable to many constructions of parlor-stoves and heaters commonly known as "base-burners," its modifications and shape being adjusted to be used beneath the ash-pit with 95 in the flues of such stoves and the same object obtained without departing from the spirit of my invention.

What I claim is—

1. In a cooking apparatus, the combination 100 with heat-conducting flues and a tray or pan arranged therein, of a flue-strip supported free from the bottom of said flue, and means constructed and arranged in the bottom of the pan, adapting it to co-operate as set forth. 105

2. In a cooking apparatus, the combination with suitable heat-conducting flues and a tray or pan adapted thereto, of a dividing flue-strip in the pan constructed and arranged, and adapted to register with walls above it, 110 whereby the products of combustion are directed. 115

3. In a cooking apparatus, the combination with suitable heat-conducting flues, of a tray or pan provided with a device adapted to register with a suspended flue-strip, whereby the products of combustion are directed, and the pan separable therefrom with its contents without disturbing the flue-strip. 120

4. In a cooking apparatus, the combination with heat-conducting flues, of a tray or pan provided with a device adapted to register with a suspended flue-strip, their meeting surfaces constructed and arranged to provide a wedge-like action, and furnished with a suitable bail, as set forth. 125

5. In combination with a cooking apparatus, provided with rear vertical and horizontal flues beneath the oven, and a vertical ascending flue extended therefrom, of a displacement device located at the junction of the latter flue, adapted to direct the soot and 130

ashes accumulating therein, into the horizontal flue.

6. In combination with a cooking apparatus, provided with rear diving flue and horizontal flue beneath the oven, a removable tray or pan in said flue, a vertical ascending flue extended therefrom, of an agitating device located on the bottom of said flue at their junction, and means for operating the same,

whereby the soot and ashes accumulating in the vertical flue may be directed into the pan.

In testimony whereof I have set my hand, this 13th day of June, 1898, in the presence of two subscribing witnesses.

JOHN H. GOODFELLOW.
